[57] CLAIM

The ornamental design for a fishing rod holder with strike signal, as shown and described.

DESCRIPTION

FIG. 1 is a front and top perspective view of a fishing rod holder with strike signal showing my new design;

FIG. 2 is a front elevational view thereof;

FIG. 3 is a rear elevational view thereof;

FIG. 4 is a top plan view thereof;

FIG. 5 is a right side elevational view thereof, with the left side elevation being a mirror image;

FIG. 6 is a bottom plan view thereof;

FIG. 7 is a front and top perspective view of a second embodiment thereof;

FIG. 8 is a front elevational view of the embodiment of FIG. 6;

FIG. 9 is a bottom plan view of the embodiment of FIG. 6;

FIG. 10 is a top plan view of the embodiment of FIG. 6;

FIG. 11 is a right side elevational view of the embodiment of FIG. 6, with the left side elevational view being a mirror image; and,

FIG. 12 is a rear elevational view of the embodiment of FIG. 6.
